INNER TUBE DRIER

Clarence Taarud, Sioux Falls, S. Dak.

Application March 22, 1933. Serial No. 662,186

6 Claims. (Cl. 15—104)

This invention relates to a drier or wiper and has for the primary object, the provision of a device of the above stated character which is especially adapted for removing water from an inner tube after the testing of the latter for leaks and which is so constructed as to direct the water removed from the tube back into the testing container.

Another object of this invention is the provision of a device of the above stated character which besides conditioning an inner tube so that it will quickly dry for reinsertion into the tire, it may also be easily and quickly installed into a testing container or support.

15 With these and other objects in view this invention consists in certain novel features of construction, combination and arrangement of parts to be hereinafter more fully described and claimed.

20 For a complete understanding of my invention, reference is to be had to the following description and accompanying drawing, in which

Figure 1 is a side elevation partly in section illustrating a drier constructed in accordance 25 with my invention.

Figure 2 is a top plan view illustrating the same.

Figure 3 is an end elevation illustrating the means of connecting the device to a support or 30 test container.

Referring in detail to the drawing, the numeral 1 indicates a substantially rectangular shaped plate having a notch 2 opening outwardly through the upper edge of the plate for the 35 purpose of receiving an inner tube after the testing of the latter for leaks in the water of a container 3. The lower edge of the plate 1 is bent upon itself to form a substantially V-shaped trough 4 to which is secured a supporting bracket 5 adapted for detachably connecting the device to the container 3 so that one end of the trough is disposed over the container and said trough supported at an inclination to drain water caught thereby into the container.

40 The bracket 5 consists of diverging arms bent angularly and bifurcated to form spaced ears 6 to receive the upper edge of the container and cooperating with the ears are set bolts 7 to be turned in engagement with the container for firmly anchoring the bracket to the container.

Links 8 and 9 are pivoted to the plate 1 and are arranged laterally of each other. A plate 10 is pivoted to the other end of the links and is provided with a notch 11 so that when the 55 plate 10 is brought into overlapping relation with

the plate 1 the inner tube will also be received within the notch 11. The walls of the notches 2 and 11 cooperate in removing water from the tube during the movement of said tube relative to said plate. A coil spring 12 is connected to the plate 1 and to the link 9, adjacent the latter's connection to the plate 10, for the purpose of retaining the latter either in a full line position, as shown in Figure 1, or in a dotted line position. The plate 10 when in the dotted line position is urged against the tube by the spring 12 with sufficient pressure to assure the removal of the water from the tube when the latter with its frictional contact with the walls of the notches is moved relative to the plate.

70 A guide flange 13 is carried by the plate 1 to receive the free end of the plate 10 when the latter is moved in overlapping relation with the plate 1. The plate 10 at its upper edge is formed with a flange 14 providing a finger piece as well as a stop adapted to engage the upper end of the guide flange 13 for limiting the movement of the plate 10 relative to the plate 1 when said plate 10 is brought in overlapping relation with respect to the plate 1.

75 While I have shown and described the preferred embodiment of my invention, it will be understood that minor changes in construction, combination and arrangement of parts may be made without departing from the spirit and scope of my invention, as claimed.

80 Having described the invention, I claim:

1. A wiper comprising a plate having a notch to receive an inner tube after the testing of the latter in water, means for supporting said plate, and means cooperating with the plate to remove the water from the tube during the movement of the tube relative to said means and the plate.

2. A wiper comprising a plate, a bracket carried by the plate for attaching the latter to a support, said plate having a notch to receive an inner tube after the testing of the latter in water, and a second plate pivoted to the first plate and having a notch to receive the inner tube when the second plate is moved in overlapping relation with respect to the first plate.

3. A wiper comprising a plate having a notch to receive an inner tube after the testing of the latter in water, links pivoted to the plate, a second plate pivoted to the links and having a notch adapted to register with the first notch when the second plate is brought into overlapping relation with the first plate, and tension means between the first plate and one of the links.

4. A wiper comprising a plate having a notch

to receive an inner tube after the testing of the latter in water, links pivoted to the plate, a second plate pivoted to the links and having a notch adapted to register with the first notch when the 5 second plate is brought into overlapping relation with the first plate, tension means between the first plate and one of the links, and a guide flange on the first plate to receive the second plate when the latter moves into overlapping relation 10 with the first plate.

5. A wiper comprising a plate having a notch to receive an inner tube after the testing of the latter in water, links pivoted to the plate, a second plate pivoted to the links and having a 15 notch adapted to register with the first notch when the second plate is brought into overlapping relation with the first plate, tension means between the first plate and one of the links, a guide flange on the first plate to receive the second plate when the latter moves into overlapping relation 20 with the first plate, and a flange on the second plate forming a combined finger

piece and stop to engage one end of the guide flange when the second plate is in full overlapping relation with the first plate.

6. A wiper comprising a plate having a notch to receive an inner tube after the testing of the latter in water, links pivoted to the plate, a second plate pivoted to the links and having a notch adapted to register with the first notch when the second plate is brought into overlapping relation with the first plate, tension means between the first plate and one of the links, a guide flange on the first plate to receive the second plate when the latter moves into overlapping relation with the first plate, a flange on the second plate forming a combined finger piece and stop to engage one end of the guide flange when the second plate is in full overlapping relation with the first plate, a flange on the second plate forming a combined finger piece and stop to engage one end of the guide flange when the second plate is in full overlapping relation with the first plate, and a trough formed on the first plate and underlying the notch thereof and extending the full length of the 95 first plate.

CLARENCE TAARUD.
